FLOWER VASE

Application filed October 4, 1930. Serial No. 486,350.

This invention relates to flower vases of the kind commonly employed in cemeteries, and which are provided with a part which may be inserted into the ground to hold the 5 vase in upright position.

The objects of this invention are to provide a vase of this kind, which is made of a single piece of sheet metal and the lower end of which is so formed that it can be readily inserted into the ground; also to provide a vase 10 of this kind of tapering form and having the portions adjacent to the lower pointed end pressed inwardly to form a plurality of concave faces and to materially reduce the cross 15 sectional area of this portion of the vase so that the same can be readily forced into and securely held in the ground; also to improve vases of this kind in other respects herein- 20 after mentioned.

20 In the accompanying drawings:

Fig. 1 is an elevation of a vase embodying this invention showing other vases nested therein, and showing the vase nested within another vase which is shown in section;

25 Fig. 2 is a top plan view of a vase embodying this invention;

Fig. 3 is an elevation on an enlarged scale of the lower or indented portion of the vase; and

30 Fig. 4 is a cross section on line 4—4, Fig. 1.

Vases of this kind have heretofore been made of sheet metal and of tapering form, but in each instance some other part is secured to the vase, which other part is inserted 35 into the ground to support the vase in an upright position. This other part, which was commonly in the form of a nail or prong, is easily loosened or broken from its connection with the vase, and when loosened renders 40 the vase inoperative by causing leaks. These vases have the further objection that they cannot be economically shipped, for the reason that the nail or projection prevents close nesting of the several vases. These objections are overcome by the construction 45

herein shown, in which the vase itself may be made of sheet metal formed into tapering shape in the usual manner as was heretofore done, but in which a part of the vase itself is formed to be inserted into the ground.

50 *a* represents the usual tapering body portion of the vase, the upper end of which is preferably provided with a bead *a*, and the vase may be provided with the usual seam (not shown), which may be welded, soldered, or otherwise made water-tight, and the lower end or point *B* of the vase is also made water-tight in any suitable manner. Vases of true 55 conical form throughout their length cannot be readily inserted into the ground, especially if the ground is dry or hard, and even if a vase of this kind is inserted into the ground, it is very apt to be dislodged.

60 In accordance with my invention, the lower portion of a vase of conical or other tapering shape is provided with a plurality of indentations *C*, each formed by pressing the metal adjacent to the point of the vase inwardly toward the axis of the vase, each indentation 65 extending upwardly from the pointed end of the vase. In the particular construction shown, three indentations are provided, each extending approximately around one third of the circumference of this part of the vase, but it will be obvious that any desired number 70

75 of such indentations may be employed. The indentations have the effect of very materially decreasing the cross sectional area of the indented portion of the vase, and also of forming concaved faces which offer increased 80 resistance to tipping over or dislodging of the vase from the ground by lateral pressure on the upper portion of the vase. The reduced cross sectional area of the indented portion of the vase reduces very materially 85 the pressure necessary to force the vase into the ground and also increases the strength of the lower part of the vase and the resistance of the same to bending or deformation.

90 The indentations in the lower end of the

vase result in the formation of a corresponding number of ribs D in which two thicknesses of metal are in close proximity to each other. These ribs, extending radially in different directions from the center or axis of the vase and upwardly from the pointed end of the vase, form a structural shape at the lower part of the vase, which offers a materially increased resistance to bending or deformation of this part of the vase.

Since the portion of the vase, which is to be inserted into the ground, has concaved faces, a further concaving or indenting of this portion of the vase by forcing the same into the ground is practically impossible, and consequently, the vase is not damaged or weakened by the pressure necessary to force the bottom of the same into the ground, as would be the case if a truly conical vase were forced into the ground, in which case indentations might be made in an irregular way in the base of the vase by the resistance of the ground, so that the base of the vase would become broken or materially weakened.

The vases formed as described have the advantage that they can be nested one within another in such a manner that a much larger number of these vases can be arranged in the space formerly required for a smaller number of vases. This is due mainly to the fact that even the indented portions of the vases can enter into corresponding portions of other vases. This effects a material saving in transportation handling and storage charges.

The vase described has the advantages of being of greater strength than vases of this kind heretofore made, and of being less expensive to construct, since the entire vase is made of a single piece of material. The vase described also eliminates the weakness of vases of this kind heretofore made, namely, the connection between the vase proper and the usual nail or other projection to be forced into the ground.

I claim as my invention:

1. A vase of substantially conical form having indentations therein adjacent to the apex to reduce the cross sectional area of the base portion of the vase to facilitate the insertion of the same into the ground.

2. A substantially conical vase having the portion thereof adjacent to the apex provided with a plurality of concave depressions and outwardly projecting ribs arranged between said depressions, resulting in portions of the walls of the vase being arranged in close proximity to each other to form a structural shape offering high resistance against deformation.

3. A vase of substantially conical form and having the base thereof adjacent to the apex provided with a plurality of indentations spaced apart, and outwardly extending ribs between said indentations, which strengthen the base portion against deformation, the in-

dented base portion being of small cross sectional area to reduce resistance of the base in entering the ground.

4. A vase made of a single piece of sheet metal formed into tapering shape, and having the lower portion thereof adjacent to the pointed end provided with a series of spaced concave depressions, the portions of the vase between said depressions forming ribs extending upwardly from said pointed end and outwardly from the axis of the vase.
